Primary Examiner — Dominic V Simone*(74) Attorney, Agent, or Firm* — Kilpatrick Townsend & Stockton LLP**(57) CLAIM**

The ornamental design for a shoe, as shown and described.

DESCRIPTION

FIG. 1 is a front lateral perspective view of an embodiment of a shoe.

FIG. 2 is a lateral side view of the shoe of FIG. 1.

FIG. 3 is a medial side view of the shoe of FIG. 1.

FIG. 4 is a front view of the shoe of FIG. 1.

FIG. 5 is a rear view of the shoe of FIG. 1.

FIG. 6 is a top view of the shoe of FIG. 1; and,

FIG. 7 is a bottom view of the shoe of FIG. 1.

The broken lines show unclaimed subject matter only and form no part of the claimed design.

1 Claim, 7 Drawing Sheets# US D846,255 S
